UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed April 5, 1923. Serial No. 630,138.

To all whom it may concern:

Be it known that I, WILLIAM KELSO, a citizen of the United States, residing at Pittsburgh, in the county of Allegheny and State of Pennsylvania, have invented certain new and useful Improvements in Car Couplers; and I do hereby declare the following to be a full, clear, and exact description of the invention, such as will enable others skilled in the art to which it appertains to make and use the same.

My invention relates to the construction of car couplers of the Master Car Builders' type and particularly to that form commonly known as the standard D-coupler.

The principal object of the invention is to provide simple and reliable means for preventing the coupler lock from accidentally moving to an unlocked position when the device is in service.

Generally stated, the principal feature of the invention consists in actuating the vertically movable and rearwardly swinging lock of a D-coupler by means of a lock lifter formed with a pin which is inclined with respect to the axis of swinging movement of the lock and which serves to shift the lifter from beneath a shoulder upon the coupler head when the lifter is caused to execute an unlocking movement, the lifter normally occupying a position beneath the said shoulder such that it is prevented from moving upwardly and therefore serves to restrain the lock to which it is connected from performing an accidental unlocking movement.

In the drawings which illustrate my invention as applied to the Master Car Builders' standard D-coupler,

Figure 1 is a vertical sectional view of the mechanism, the lock, knuckle opener, lock lifter and means for actuating the latter being shown in elevation and in locked position.

Fig. 2 is a transverse sectional view of the construction shown in Fig. 1, portions of the device being broken away and the parts being shown in locked relation.

Fig. 3 is a detail view corresponding to Fig. 2, showing a portion of the mechanism therein illustrated, the parts being in the positions they occupy when the coupler lock is released for an unlocking movement.

Fig. 4 is a detail view partly in elevation

and partly in longitudinal section showing the relation assumed by the lifter and lock when the latter has been released from the control of the means for preventing its accidental unlocking.

In the drawings, 1 indicates the coupler head and 2 is the knuckle pivotally mounted thereon by means of the usual knuckle pin 3. The knuckle 2 is normally restrained from performing an uncoupling rotation by means of a vertically sliding and rearwardly swinging lock 4 which is supported when in locked position upon a horizontally rotatable knuckle opening lever 5 operating within the coupler head. The upper part of the lock 4 is of comparatively large and heavy cross section and normally stands in the path of movement of the tail of the knuckle while the lower portion of the lock is in the form of a leg 6 which extends downwardly so as to project through an opening 7 in the lower wall of the coupler head. After the lock 4 has been raised vertically a sufficient distance to permit outward rotation of the knuckle 2, the depending leg 6 swings rearwardly and by pressing against the adjacent end of the knuckle opener 5 causes the latter to rotate, thereby throwing the knuckle to open position in the well understood manner.

While the standard D-coupler is provided with means designed to prevent the lock from creeping upward and thus accidentally assuming an unlocked position, the nature of the parts of the device and their relations are such that the desired result is not unfailingly accomplished under all circumstances. The specific object of the present invention is to remedy this defect. To this end the leg 6 of the lock is provided near its lower end with an opening, socket or recess 8 which is inclined in a direction transversely of the coupler head and which preferably is of circular cross section, the higher end of said opening being at the side of the lock which is adjacent the knuckle. This inclined recess receives a pin 9 carried by and preferably cast integral with a lock lifter member 10 whose upper end 11 normally stands under the usual anti-creep shoulder or lug 12 with which the head of the D-coupler is provided at a point adjacent the side of the lock 4 opposite the

knuckle 2. The pin 9 which is preferably circular in cross section is of somewhat less diameter than the opening 8 in the lower end of the lock 4, thus enabling the lock 5 lifter 10 to have a swinging movement toward the lock resulting in the withdrawal of the upper end of said lifter from beneath the anticreep shoulder 12 of the coupler head, as well as providing clearance for allowing the pin 9 to turn within the opening 8 of the lock so as to permit said lock to execute its rearward swinging movement. The upper end 11 of the lock lifter may advantageously be inclined or beveled, as 15 shown, to correspond substantially to the inclination of the pin 9, thereby enabling the upper end of said lifter to stand but a short distance below the anticreep shoulder 12 of the coupler head when the parts are in 20 locked position, and at the same time thereby affording sufficient clearance between said shoulder and the lifter to permit the latter to pass from beneath the anticreep shoulder. By this means the upper end of the lifter 25 10 is caused to engage the anti-creep lug 12 when the lock has moved upwardly a very short distance.

The lifter 10 is preferably actuated by a swinging arm or lever 13 pivotally mounted 30 upon the under side of the coupler head 1 by means of a pin 14. This operating lever 13 and the manner of pivotally mounting it upon the coupler head may advantageously be identical with similar features of construction of the standard D-coupler. The 35 lifter 10 is pivotally connected to the swinging lever 13 by means of a pivot pin or rivet 15, the connection between the parts 10 and 13 being such that the lifter 10 is 40 capable not only of executing a pivotal movement in the direction of length of the coupler, but also of swinging transversely of the coupler so as to cause its inclined pin 9 to slide in the recess or opening 8 of 45 the lock.

Except for the differences heretofore described the parts of the coupler mechanism are preferably constructed like the corresponding parts of the standard D-coupler. 50 It will be appreciated, however, that while my invention is especially applicable to the D type of coupler, it is susceptible of application to other forms of coupler mechanism as well.

55 When the lever 13 is swung upwardly in the operation of unlocking the coupler the upward movement of the lock lifter 10 with respect to the lock causes the inclined pin 9 to slide inwardly in the corresponding 60 inclined opening 8 at the lower end of the lock 4, thus causing the upper end 11 of the lifter to move from beneath the cooperating shoulder 12 of the coupler head 1. When the upper end of the lifter has thus been 65 withdrawn from beneath the shoulder 12 the

continued upward movement of the operating member 13 and lifter 10 effects an extended unlocking movement of the lock 4.

I claim:—

1. In a car coupler, the combination with 70 a coupler head, of a knuckle pivotally mounted thereon, a vertically movable and rearwardly swinging lock for said knuckle, and a lock lifter for actuating said lock, said lifter being slidably and pivotally connected 75 to said lock so as to be capable of sliding with respect thereto transversely of said head and also being capable of pivoting with respect to said lock when the latter executes its rearward swinging movement, 80 and said head having a shoulder which is adapted to cooperate with said lifter when the latter is in locked position to prevent said lock from accidentally moving to unlocked position. 85

2. In a car coupler, the combination with 90 a coupler head, of a knuckle pivotally mounted thereon, a vertically movable and rearwardly swinging lock for said knuckle, and a lock lifter for actuating said lock, 95 said lifter being rotatably connected to said lock to permit the latter to execute its swinging movement and being movable laterally toward said knuckle to withdraw it from beneath a shoulder upon the coupler head, and said head being provided adjacent the side of the lock which is opposite the knuckle with a shoulder adapted to cooperate with said lifter to prevent said lock from accidentally moving to unlocked position. 100

3. In a car coupler, the combination with 105 a coupler head, of a knuckle pivotally mounted thereon, a lock for said knuckle, and a lock lifter for actuating said lock, said head being provided with a shoulder adapted to be engaged by said lifter to prevent said lock from accidentally moving to unlocked position, said lock being capable of swinging movement and having a recess 110 which is inclined transversely of the coupler head, and said lifter being provided with a pin which is inclined with respect to the axis of swinging movement of said lock and which extends into and is adapted to slide 115 and turn within said recess. 110

4. In a car coupler, the combination with 120 a coupler head, of a knuckle pivotally mounted thereon, a lock for said knuckle, said lock being adapted to have a swinging movement, a lock lifter for actuating said lock, and means for operatively connecting said lifter to said lock to permit the latter to execute its swinging movement, said head being provided with a shoulder adapted to 125 be engaged by said lifter to prevent said lock from accidentally moving to unlocked position, and said means involving a pin which is inclined with respect to the axis of swinging movement of said lock and 130

which serves to shift said lifter from beneath said shoulder when the lifter is caused to execute an unlocking movement.

5. In a car coupler, the combination with 5 a coupler head, of a knuckle pivotally mounted thereon, a lock for said knuckle adapted to have a swinging movement, and a lock lifter for actuating said lock, said lifter and lock having a pin and recess connection, 10 said pin being inclined to the horizontal, and said head being provided with a shoulder adapted to be engaged by said lifter to prevent said lock from accidentally moving to unlocked position.

15 6. In a car coupler, the combination with a coupler head, of a knuckle pivotally mounted thereon, a vertically movable and rearwardly swinging lock for said knuckle, and a lock lifter for actuating said lock, 20 said lifter being provided with a pin which is inclined to the horizontal, said lock having an opening which is inclined to correspond substantially to said pin and within which said pin is slidable, and said head being provided with a shoulder adapted to 25 be engaged by said lifter to prevent said lock from accidentally moving to unlocked position.

7. In a car coupler, the combination with 30 a coupler head, of a knuckle pivotally mounted thereon, a lock for said knuckle

adapted to have a swinging movement, a lock lifter for actuating said lock, and means pivotally mounted on said coupler head for actuating said lifter, said lifter being provided with a pin which is inclined to the horizontal, said lock being formed with a correspondingly inclined opening into which said pin extends, said lifter and said means for actuating it being pivotally 35 connected by means permitting said pin to slide in said opening, and said head being formed with a shoulder adapted to be engaged by said lifter to prevent said lock from accidentally moving to unlocked position. 40

8. In a car coupler, the combination with a coupler head, of a knuckle pivotally mounted thereon, a lock for said knuckle capable of swinging movement, and a lock 50 lifter for actuating said lock, said lifter being pivotally connected to said lock and capable of sliding with respect thereto transversely of the plane of swinging movement of said lock, and said head having a 55 shoulder adapted to cooperate with said lifter when the latter is in locked position to prevent said lock from accidentally moving to unlocked position.

In testimony whereof I affix my signature.

WILLIAM KELSO.
